MIXING APPARATUS

Mark Plunguiian, Gillette, and Jesse L. Riley, East Orange, N. J., assignors to Celanese Corporation of America, New York, N. Y., a corporation of Delaware

Application October 1, 1949, Serial No. 119,121

6 Claims. (Cl. 259—6)

1

This invention relates to mixing apparatus and relates more particularly to mixing apparatus for blending a fibrous solid and a liquid.

As is well known, in the preparation of organic acid esters of cellulose, a cellulosic material, preferably after a suitable pretreatment to increase its reactivity, is esterified by treatment with an organic acid anhydride in the presence of an esterification catalyst and a solvent for the ester being formed. During the esterification, it is necessary to achieve an intimate contact between all of the cellulosic material and the esterification medium, and also to control the temperature of the esterification mixture closely so as to obtain a product having the desired properties.

Heretofore, it has been the practice to carry out the esterification of the cellulosic material on a batch basis in jacketed vessels equipped with simple low speed stirrers of the paddle blade or helical ribbon type. The time required for the complete esterification of the cellulosic material has been at least several hours and it was found that during this time the low speed stirrers produced an adequate contact between the cellulosic material and the esterification medium. It was also found that the temperature of the esterification mixture could be closely controlled by passing a heat-transfer medium at a suitable temperature through the jacket surrounding the reaction vessel.

However, when due to improvements in the process, the time required for the esterification of the cellulosic material was reduced to a fraction of its previous value, say to less than one hour, it was found that the low speed stirrers failed to produce an adequate contact between the cellulosic material and the esterification medium. The low speed stirrers also failed to break up any lumps or wads of cellulosic material that were present in the esterification mixture, with the result that these wads and lumps were not fully esterified and the cellulose ester that was formed contained an appreciable quantity of unesterified or incompletely esterified cellulosic material. With a short reaction time, it was also found that the heat liberated during the esterification caused an excessive rise in the temperature of the esterification mixture resulting in a degradation of the cellulose molecule and the production of a cellulose ester that was not suited for the preparation of filaments and films. In addition, the esterification of the cellulosic material on a batch basis rather than in a continuous manner was found to be highly inefficient.

2

when the time required for the esterification was reduced to less than one hour.

It is an important object of this invention to provide a mixing apparatus which will be free from the foregoing and other disadvantages and which will be especially simple in construction and efficient in operation.

A further object of this invention is the provision of a mixing apparatus which is particularly adapted to blending a fibrous solid and a liquid.

Other objects of this invention will be apparent from the following detailed description and claims.

15 A preferred embodiment of our invention will now be described with particular reference to the accompanying drawing wherein

Fig. 1 is an isometric view, partly in section and partly broken away, showing the general arrangement of the mixing apparatus;

20 Fig. 2 is a longitudinal cross-sectional view of the mixing apparatus shown in Fig. 1,

Fig. 3 is a longitudinal cross-sectional view, on a reduced scale, showing the ducts for passing 25 a heat-transfer medium through the stirring blades of the mixing apparatus shown in Fig. 1,

Fig. 4 is a cross-sectional detail view of a modified form of mixing apparatus, and

Fig. 5 is a cross-sectional view taken on the line 5—5 in Fig. 4 in the direction of the arrows.

Referring now to the drawing, the reference numeral 11 designates a hopper into which the cellulosic material to be esterified is entered, which hopper 11 opens into a passageway 12 extending through a casing 13. The passageway 12 has a cross-sectional contour defined by the peripheries of two intersecting curves of generally circular shape, whose centers are spaced apart a distance greater than the radius of either of the curves and less than the sum of the radii of the curves. With this spacing between the centers of the curves, the distance between the projections 14 and 15 on the contour of the passageway 12 at the point where the peripheries of the two generally circular curves intersect is less than the diameter of either of said curves. If the spacing between the centers of the curves is less than the value specified, the passageway 12 will not be large enough to accommodate the elements positioned therein as will be more fully described hereinafter. On the other hand, if the spacing between the centers of the curves is larger than the value specified, the curves will not intersect.

Shafts 16 and 17, which are rotated in syn-

chronism and in opposite directions by any suitable means (not shown), extend across the base of the hopper 11 and through the passageway 12 axially of the curves whose peripheries define the contour of said passageway. Mounted on the shafts 16 and 17 at the base of the hopper 11 and for a short distance into the passageway 12 are feed screws 18 and 19, which serve to feed the cellulosic material from said hopper into and through said passageway. As the cellulosic material enters the passageway 12, it is contacted with an esterification medium that is fed into said passageway from a conduit 20 extending through the casing 13. The cellulosic material and esterification medium are blended and brought into intimate contact with each other in the passageway 12 by intermeshing, multi-lobed stirring blades 21 and 22 mounted on the shafts 16 and 17, respectively, and extending longitudinally of the passageway 12. The cross-sectional contours of the stirring blades 21 and 22 are trochoidal, being either generally epicycloidal or epitrochoidal so that the clearance between the stirring blades 21 and 22 themselves, or between said stirring blades and the walls of the passageway 12, will not vary widely as the shafts 16 and 17 are rotated. The term "trochoidal" is employed in the appended claims to define an epicycloid or epitrochoid. After traversing the passageway 12, the esterified cellulosic material enters a conduit 23 positioned midway between the shafts 16 and 17, through which conduit the esterified material is discharged from the mixing apparatus.

To control the temperature of the esterification mixture during the esterification, the casing 13 is provided with a jacket 24 through which a heat-transfer medium at a suitable temperature may be circulated from conduits 25. In addition, the stirring blades 21 and 22 are each provided with ducts 26 into which a heat-transfer medium is entered from communicating ducts 27 in the shafts 16 and 17 and from which it is discharged through communicating ducts 28 in said shafts.

The dimensions of the stirring blades 21 and 22, which effect the blending of the cellulosic material and esterification medium in the passageway 12, are selected to provide a sufficient clearance between the stirring blades 21 and 22 themselves, and/or between said stirring blades and the walls of the passageway 12 so that the material in said passageway will continually flow through said clearance when the shafts 16 and 17 are rotated. Any stagnation or hold-up of the material is thereby avoided. While the exact amount of such clearance will depend upon the nature and viscosity of the materials being blended, it is desirable to employ a minimum clearance of about 0.03 inch at at least one of these places. If a smaller clearance is employed, the stirring blades 21 and 22 will tend to act as pumps rather than mixers, forcing the material in the passageway 12 transversely of the shafts 16 and 17, developing excessive pressures in the casing 13 and greatly increasing the power required to drive said shafts. Instead of only two lobes, each of the stirring blades 21 and 22 may have a greater number of lobes so long as the lobes intermesh with each other. To accommodate the stirring blades 21 and 22, the centers of the curves whose peripheries define the contour of the passageway 12 must, as pointed out above, be spaced apart a distance greater than the radii of either of said curves.

As the shafts 16 and 17 rotate, the materials in the passageway 12 will be carried by the stirring blades 21 and 22 into the clearance between said stirring blades themselves, at which point they will be thoroughly blended and any wads or lumps therein will be crushed and dispersed. In addition, the rotation of the shafts 16 and 17 will force the materials in the passageway 12 through the clearance between the stirring blades 21 and 22 and the walls of the passageway 12, at which point a further blending of said materials will take place. The clearance between the stirring blades 21 and 22 themselves may be equal to the clearance between said stirring blades and the walls of the passageway 12. However, it is preferred to make the clearance between the stirring blades 21 and 22 themselves, at which point the most effective blending takes place, somewhat larger, say at least about 2 to 3 times as large as the clearance between said stirring blades and the walls of the passageway 12 so that the major portion of the materials being blended will be forced through the clearance between the stirring blades 21 and 22 themselves during each revolution of the shafts 16 and 17.

The clearance between the stirring blades 21 and 22 themselves, and between said stirring blades and the walls of the passageway 12 may be constant for the entire length of said stirring blades. Alternatively, one or both of said clearances may be varied longitudinally of the stirring blades, particularly when the viscosity of the materials being blended changes during their passage through the mixing apparatus. This variation in clearance may be obtained by altering the cross-sectional area of the passageway 12, by altering the cross-sectional area of the stirring blades 21 and 22, by inclining the shafts 16 and 17 on which the stirring blades 21 and 22 are mounted, with respect to each other, or by a combination of these expedients.

The clearance between the stirring blades 21 and 22 themselves, and between said stirring blades and the walls of the passageway 12 may remain constant as the shafts 16 and 17 rotate. However, an adequate blending of the materials in the passageway 12 will also be obtained if these clearances vary during the rotation of the shafts 16 and 17. This variation in clearance will take place, if the curves whose peripheries define the contours of the passageway 12 are not truly equal and circular, if the shafts 16 and 17 are not positioned axially of said curves, and if the contours of the stirring blades 21 and 22 are not truly epitrochoidal or hypotrochoidal. It is also possible to eliminate the projections 14 and 15 from the contour of the passageway 12 and employ a passageway free from reentrant angles. However, this will produce a dead space in the passageway 12 through which the stirring blades 21 and 22 will not pass and in which the materials being blended will accumulate.

Not only are the materials traversing the passageway 12 effectively and rapidly blended, but the temperature of said materials is maintained within close limits, since, with each revolution of the shafts 16 and 17, all of said materials pass in the form of a relatively thin film through the clearance between the stirring blades 21 and 22 themselves, and between said stirring blades and the walls of the passageway 12. In this manner, all of the materials being blended are brought repeatedly into intimate contact with a surface

5

whose temperature is controlled by a heat-transfer medium.

A modified form of mixing apparatus especially suited for use at high rates of material flow is shown in Figs. 4 and 5 of the drawing. In this modification grooves 29 and 31 are provided circumferentially of the stirring blades 21 and 22, respectively, and parallel baffle disks 32 and 33 mounted transversely of the shafts 16 and 11, respectively, extend into said grooves. The baffle disks 32 and 33 overlap each other forming a barrier to the flow of the materials being blended along the center of the passageway 12, forcing said materials to flow through the clearance between said baffle disks and the walls of said passageway and thereby avoiding the channeling which might otherwise take place at high rates of material flow. Alternatively, the materials being blended may be led around the baffle disks 32 and 33 by means of one or a plurality of conduits opening through the casing 13 into the passageway 12 and extending from one side of said baffle disks to the other. In this case, no clearance is necessary between the baffle disks 32 and 33 and the walls of the passageway 12. Treating agents may advantageously be added to the materials in the passageway 12 as said material flow around the baffle disks 32 and 33 and will be thoroughly blended with said materials by the stirring blades 21 and 22.

While the mixing apparatus of this invention has been described with particular reference to the preparation of organic acid esters of cellulose, it may also be employed for other purposes and with other materials. In addition, the mixing apparatus of this invention may be used for blending materials on a batch basis as well as in a continuous manner by entering a charge into the passageway 12, holding the charge in said passageway until the desired blending has taken place and then removing the charge from said passageway.

It is to be understood that the foregoing detailed description is given merely by way of illustration and that many variations may be made therein without departing from the spirit of our invention.

Having described our invention, what we desire to secure by Letters Patent is:

1. In a mixing apparatus, the combination with a casing having a passageway extending therethrough, said passage having a cross-sectional contour defined by the peripheries of two intersecting curves of generally circular shape, of means for feeding material to and longitudinally through said passageway, a pair of multi-lobed stirring blades in said passageway for operating on said material, at least one of the clearances between said stirring blades themselves and between said stirring blades and the walls of said passageway being sufficient to permit material in said passageway to pass through said clearance when the stirring blades are rotated, said stirring blades having a contour of trochoidal shape whereby the clearance between the stirring blades themselves and the stirring blades and the walls of the passageway will remain substantially constant as the stirring blades are rotated, and means for discharging the material from the passageway.

2. In a mixing apparatus, the combination with a casing having a passageway extending therethrough, said passageway having a cross-sec-

6

tional contour defined by the peripheries of two intersecting curves of generally circular shape, of means for feeding material to and longitudinally through said passageway, a pair of multi-lobed stirring blades in said passageway for operating on said material, at least one of the clearances between said stirring blades themselves and between said stirring blades and the walls of said passageway being a minimum of 0.03 inch to permit material in said passageway to pass through said clearance when the stirring blades are rotated, said stirring blades having a contour of trochoidal shape whereby the clearance between the stirring blades themselves and the stirring blades and the walls of the passageway will remain substantially constant as the stirring blades are rotated, and means for discharging the material from the passageway.

3. In a mixing apparatus, the combination with a casing having a passageway extending therethrough, said passageway having a cross-sectional contour defined by the peripheries of two intersecting curves of generally circular shape, of means for feeding material to and longitudinally through said passageway, a pair of multi-lobed stirring blades in said passageway for operating on said material, at least one of the clearances between said stirring blades themselves and between said stirring blades and the walls of said passageway being a minimum of 0.03 inch to permit material in said passageway to pass through said clearance when the stirring blades are rotated, said stirring blades having a contour of trochoidal shape whereby the clearance between the stirring blades themselves and the stirring blades and the walls of the passageway will remain substantially constant as the stirring blades are rotated, means operatively connected to said stirring blades for passing a heat transfer medium therethrough, and means for discharging the material from the passageway.

4. In a mixing apparatus, the combination with a casing having a passageway extending therethrough, of a plurality of shafts in said passageway, multi-lobed stirring blades, having grooves therein, mounted on said shafts in intermeshing relationship, at least one of the clearances between said intermeshed stirring blades and between said stirring blades and the walls of said passageway being sufficient to permit materials in said passageway to pass through said clearance when the stirring blades are rotated, and baffle disks, mounted on said shafts in said grooves in said stirring blades, the baffle disks on one of said shafts being parallel to and in overlapping relationship with the baffle disks on another of said shafts for preventing the material in said passageway from flowing along the center of said passageway.

5. In a mixing apparatus, the combination with a casing having a passageway extending therethrough, of a plurality of shafts in said passageway, multi-lobed stirring blades, having grooves therein, mounted on said shafts in intermeshing relationship, at least one of the clearances between said intermeshed stirring blades and between said stirring blades and the walls of said passageway being sufficient to permit materials in said passageway to pass through said clearance when the stirring blades are rotated, and baffle disks, mounted on said shafts in said grooves in said stirring blades, the baffle disks on one of said shafts being parallel to and in

overlapping relationship with the baffle disks on another of said shafts for preventing the material in said passageway from flowing along the center of said passageway, the clearance between said baffle disks and the walls of said passageway being sufficient to permit materials in said passageway to pass through said clearance.

6. In a mixing apparatus, the combination with a casing having a passageway extending therethrough, said passageway having a cross-sectional contour defined by the peripheries of two intersecting curves of generally circular shape, of a plurality of shafts in said passageway, multi-lobed stirring blades, having grooves therein, mounted on said shafts in intermeshing relationship, said stirring blades having a contour of trochoidal shape, at least one of the clearances between said intermeshed stirring blades and between said stirring blades and the walls of said passageway being sufficient to permit materials in said passageway to pass through said clearance when the stirring blades are rotated, and

8
circular baffle disks, mounted on said shafts in said grooves in said stirring blades, the baffle disks on one of said shafts being parallel to and in overlapping relationship with the baffle disks on another of said shafts for preventing the material in said passageway from flowing along the center of said passageway.
